UNITED STATES PATENT OFFICE.

BERTALAN KALMAR AND MANO KOLLIN, OF LONG ISLAND CITY, NEW YORK.

ELECTRIC SOLDERING IRON.

Application filed October 21, 1927. Serial No. 227,637.

This invention relates generally to electrical devices and has more particular reference to a novel electric soldering iron.

The invention has for an object the provision of a device of the class mentioned which is of simple, efficient, durable construction, and which can be manufactured and sold at a reasonable cost.

The invention consists in providing a soldering iron with a removable heating point of any shape or construction, formed with a reduced rear portion accommodating heating units properly insulated with asbestos or mica sheets, the heating point being supported in a socket member, and means for normally holding the heating point against displacement being associated with the point and socket member.

For further comprehension of the invention and of the objects and advantages thereof reference will be had to the following description and accompanying drawings, and to the appended claims in which the various novel features of the invention are more particularly set forth.

Referring to the accompanying drawing forming a material part of this disclosure:

Fig. 1 is a perspective view of a device constructed according to this invention.

Fig. 2 is a perspective view of a modified form of this invention.

Fig. 3 is a fragmentary perspective view of the invention provided with a modified form of heating point.

Fig. 4 is a fragmentary face view of a modified heating point for use in the invention.

Fig. 5 is a fragmentary sectional view of the device taken as for example on the line 5-5 of Fig. 1.

Fig. 6 is a vertical sectional view thereof taken on the line 6-6 of Fig. 5.

Fig. 7 is a fragmentary perspective view of the heating units used in this invention, and of a small front wedge, and a larger rear wedge engaged over the wire connection between the heating units.

Fig. 8 is a fragmentary face view of one of the heating units, with the upper parts broken away so as to disclose the lower parts.

Fig. 9 is a horizontal sectional view taken on the line 9-9 of Fig. 5.

Fig. 10 is a view similar to Fig. 5 but disclosing a modified form of the invention.

The reference numeral 10 indicates generally a handle, preferably made of wood, having its lower end 10' removably arranged and being of hollow construction. A hollow rod 11 is attached to the top of the handle, and an asbestos insulation washer 12 is clamped between the top of the handle 11 and a flange 13 integral with rod 11. A socket member 14 is secured to the top of rod 11 and is provided with a central opening 15, so that a passage exists from the socket member through the rod 11 and handle 10. A cable 16 with a pair of wires 17, 18, extends through this passage.

A heating point 19 is formed with a reduced end portion 20. A heating unit 21 is placed on one side of the reduced portion 20 and another 22 is placed on the other side. The heating point 19 together with the heating units 21, 22 are slipped into the socket member 14. The wire 17 is connected with one end of the winding of heating unit 22, the other end of the winding being connected as at 23 to one end of the winding of unit 21 and the other end of the winding of unit 21 is connected to wire 18. A small asbestos or mica wedge 24 is placed on one side of the wire connection 23, and a larger wedge 25 on the other side so as to thoroughly insulate the said wire connection 23 from contact with the socket member 14 or heating point 19.

Each of the heating units 21, 22, consists of a top metallic member 26, an adjacent mica layer 27, a winding 28 under layer 27, and an asbestos layer 29 beneath the winding 28, and a metallic bottom member 29' next to layer 29, the top member 26 being formed with flaps 30 bent over against the bottom member 29' to hold the various parts together.

The heating point 19 may be formed with cavities 31 on the sides thereof so that some gripping tool may be engaged therewith for pulling the heating point out of the device. The heating point 19 may be replaced by heating points of different shapes, such as 19' shown in Fig. 4 or 19^a shown in Fig. 3, or any other shapes adapted for different kinds of work.

The heating units 21 and 22 are provided with side projections 32 engaged in recesses 33 in the socket member 14. The wedge 25 engages in grooves 34 in the sides of the heating units and a wedge 25' engages in grooves 34' in the same sides of the heating

units but at the other ends, these wedges acting to maintain the heating units with the projections 32 engaged in the recesses 33 so that the heating units will not be withdrawn when the heating point 19 is withdrawn. Fig. 7 shows the heating units 21, 22 at inclined angles to each other so that the vertical grooves in which the wedges engage may be seen. In the device, these heating units are parallel as seen in Fig. 9.

The modification of the invention illustrated in Fig. 10 discloses a means for normally securing the heating point 19 against withdrawal consisting of levers 36 hinged intermediate of their ends in the socket member 14, one end of each lever being engageable in apertures 37 in the heating point 19 and the other end of each lever engages a serrated friction surface 38 to hold the levers as positioned, which may be accomplished by inserting a tool through apertures 39 in the socket member 14 and engaging a threaded aperture 40 in each of the levers.

In Fig. 2 the socket member 14' is shown in a horizontal position.

It is to be understood that in our electric iron the heat is concentrated toward the heating point since the asbestos plate 27 is a comparatively better heat insulator than the mica plate 29, thus preventing the heat to escape through the socket member 14.

While we have illustrated and described our invention with some degree of particularity, it will be understood that the device is, nevertheless, susceptible of considerable modification therein. We therefore, reserve the privilege of resorting to all such changes as may be fairly embodied within the spirit and scope of the invention as claimed.

Having thus described our invention what we claim as new and desire to secure by United States Letters Patent is:

1. The combination with an electric soldering iron having a socket member, heating units therein, and a heating point slidably arranged between the units, of projections from the heating units engaging in recesses in the socket member, and wedges slidable in grooves in the heating units to force the

heating units against the socket member so that the projections are forced to stay in engagement with the recesses.

2. The combination with an electric soldering iron having a socket member, heating units therein, and a heating point slidably arranged between the units, of projections from the heating units engaging in recesses in the socket member, and wedges slidable in grooves in the heating units to force the heating units against the socket member so that the projections are forced to stay in engagement with the recesses, and means for normally holding the heating point against being drawn out. 60

3. The combination with an electric soldering iron having a socket member, heating units therein, and a heating point slidably arranged between the units, of projections from the heating units engaging in recesses in the socket member, and wedges slidable in grooves in the heating units to force the heating units against the socket member so that the projections are forced to stay in engagement with the recesses, and means for normally holding the heating point against being drawn out. 70

4. The combination with an electric soldering iron having a socket member, heating units therein, and a heating point slidably arranged between the units, of projections from the heating units engaging in recesses in the socket member, and wedges slidable in grooves in the heating units to force the heating units against the socket member so that the projections are forced to stay in engagement with the recesses, and means for normally holding the heating point against being drawn out, said means being manually releaseable. 80

In testimony whereof we have affixed our signatures.

BERTALAN KALMAR.
MANO KOLLIN.
